AUXILIARY BERTH ARRANGEMENT

Lewis A. Lutherman and Earl L. Thompson, Chicago, Ill., assignors to Pullman-Standard Car Manufacturing Company, Chicago, Ill., a corporation of Delaware

Application July 24, 1944, Serial No. 546,296

15 Claims. (Cl. 105—315)

1

This invention relates to railway sleeping cars and has for its primary purpose the provision of an auxiliary sleeping berth for the car porter.

An important object of the invention is the provision of a porter's berth located in the end portion of the car adjacent the facilities with which the porter's duties are associated.

Another object of the invention is the provision of a porter's berth which affords a full length bed made up at all times ready for occupancy and permanently independent of the remaining sleeping accommodations on the car and accessible from a portion of the car other than the area from which the other accommodations are entered.

The foregoing and other objects are attained by the arrangement illustrated in the accompanying drawings in which—

Fig. 1 is a longitudinal sectional view through a railway car illustrating a general elevation of sleeping accommodations including the porter's berth of this invention;

Fig. 2 is a sectional plan view of the car showing the arrangement of the sleeping accommodations in alcoves and illustrating the porter's enclosure in section;

Fig. 3 is a cross sectional view through the car outside the porter's enclosure taken on the line 3—3 of Fig. 2 and showing the entrance to the berth with access steps on the bulkhead;

Fig. 4 is a cross sectional view through the car at the opposite side of the porter's enclosure from Fig. 3 taken on the line 4—4 of Fig. 1 and showing the relation of the porter's berth to adjacent sleeping accommodations;

Fig. 5 is an enlarged cross sectional view through the car taken on line 5—5 of Fig. 1 showing the porter's berth and entrance details in front elevation;

Fig. 6 is an enlarged longitudinal sectional view through the porter's berth taken on the line 6—6 of Fig. 7 showing the general construction of the arrangement including the spring suspension for the mattress and the sash in the side wall to admit light; and

Fig. 7 is an enlarged cross sectional view through the porter's berth and an adjacent sleeping accommodation, the section being taken on the line 7—7 of Fig. 3.

The invention is applicable to a sleeping car of the type having an aisle adjacent to one side wall with sleeping accommodations disposed to one side thereof extending to the opposite side wall and arranged transversely of the car in tiers of berths which may be convertible for daytime occupancy. The tiers of berths may be disposed three high and arranged one over the other when made up for night occupancy and are provided with alcoves opening off the side aisle and affording access to the berths in each alcove independ-

2

ently of those in all of the remaining alcoves. The alcoves may be of the single type containing a single tier of three berths accessible only from the alcove provided therefor or of the double type comprising two tiers, each containing three berths and all accessible from one alcove. The berth construction of this invention is particularly adapted to cars with this type of sleeping accommodations and provides a porter's berth entirely independent of all of the other accommodations and having its own entrance completely dissociated from any of the alcoves and from the aisle of the car.

In the drawings 10 represents a railway car supported at opposite ends upon trucks 11. The car body is provided with a floor 12, end walls 13, side walls 14 and 15 and roof 16. Windows 17 as best shown in Fig. 1, are disposed in pairs in the respective side walls adjacent to convertible berths hereinafter to be described. An aisle 18 adjacent the side wall 14 extends the length of the car from end bulkhead 20 and from which all of the passenger sleeping accommodations are accessible. The end bulkhead 20 defines an end zone of the car wherein toilet facilities for the car are provided including a plurality of washbasins 21 mounted with mirrors 22 on the bulkhead and a hopper 23 disposed within an enclosure 24 having a door 25 opening to the end zone. Bracket shelves 26 are disposed over the mirrors 22 on the bulkhead 20 and a towel dispensing cabinet 27 is located upon side wall 15 together with paper cup dispenser 28. A soiled towel receptacle 29 is also located at the side wall 15, all as best shown in Fig. 1. Both the washbasins 21 and hopper 23 are supplied with water from an overhead tank 30 supported from roof framing members 31 by straps 32 passing beneath the tank. Pipe 33 connects the tank with the flushing mechanism of hopper 23 and suitable piping (not shown) connects the tank to the washbasins 21. Lighting fixtures 34 and 35 are disposed in the washroom and toilet room respectively and are mounted upon ceiling 36 which conceals the tank 30. Windows 46 and 47 are disposed in the washroom and toilet 24 respectively and guard rods 48 and 49 extend thereacross to afford an easy grab when the car sways on curves or the like.

At the opposite side of the passageway from the washroom facilities in the end zone of the car storage lockers 37 and 38 are disposed in the corner formed by side wall 14 and end wall 13. Doors 39 and 40 afford access to the respective lockers. Between these lockers and end bulkhead 20 a short transversely extending aisle 41 is defined which connects the side aisle 18 with the central passageway 42 leading to the end door 43 communicating with the passage between cars. The end zone of the car, being over a supporting truck, 60 is disposed on a higher level than the passenger

compartment and to compensate for the difference in height of the floors of the two areas a ramp 44 is provided in the aisle 18 adjacent to the end zone whereby to afford an easy approach in either direction between the two portions of the car.

In the passenger compartment of the car a plurality of accommodations are provided which are convertible between seats for daytime travel and berths for nighttime use. The accommodations are disposed transversely of the car and arranged in alcoves 45 accessible from the single side aisle 18 with the individual accommodations of each alcove being entered directly therefrom. As best shown in Figs. 1 and 2 the individual sleeping accommodations in each alcove comprise a fixed upper berth 61, a convertible intermediate berth 62 and a lower berth 63 formed by the seat used normally in daytime travel and all of which may be incorporated in an alcove either in a single tier of three such berths or, as shown, in opposed tiers of three berths each to provide alcoves each containing six accommodations. The seating capacity of the various alcoves is the same for daytime occupancy as the number of sleeping accommodations provided for night use.

The berths are supported from framework which permits of the application of the arrangement in tiers of three berths alone or in two tiers in opposed relation. The framing includes supporting posts 65 at the aisle extending from the car floor to the ceiling and posts 64 at the side wall extending from the heater pipe angle 66 to a point short of the ceiling but supporting the upper berth 61. Longitudinal framing members 67 at the ceiling connect all of the posts 65 throughout the length of the car and the posts 64 are connected by longitudinal 68 on the side wall. The longitudinal 67 extends continuously throughout the length of the passenger compartment but the member 68 extends only upon opposite sides of a side entrance door (not shown) disposed midway of the length of the car and to the end bulkhead 20.

The upper berth comprises a frame 61 supported at two corners by the posts 64 and 65 and at one of the remaining corners by the longitudinal 68. At the fourth corner of the berth adjacent the aisle the frame 61 is suspended from the longitudinal 68 by means of a supporting rod 69 secured to both and carrying the load of the berth in tension. The frame 61 is provided with spring construction 70 which is best shown in connection with the intermediate berth in Fig. 7 and a mattress 71 is resiliently supported by the frame for the complete comfort of the occupant. The intermediate berth comprises a frame 62 pivotally mounted at 72 in the posts 64 and 65 and movable between the inclined backrest position shown at the left in Fig. 1, where it cooperates with the lower berth frame 63 to provide a seat, with the mattress 71 therefor serving as cushions, to the horizontal berth position shown at the right in this same figure, where it is supported by means of folding struts 73 extending between the intermediate berth frame 62 and lower berth frame 63. The struts 73 are pivotally mounted at opposite ends of the intermediate berth in frame 62 as at 74 and when the berth is being used as a backrest in combination with the lower berth to provide a seat, the struts may be folded to retracted position in the frame 62 where they are retained by spring clip 75 as best indicated in Fig. 4. When in extended position the struts support the intermediate berth from

the lower berth frame 63. The lower berth frame 63 like the upper berth 61 is fixed and is supported at the end adjacent side wall 15 upon the heater pipe angle 66 and at the aisle end in post 65 and by a leg member 76. The lower berth frame like the intermediate and upper berth frames, is provided with spring construction 70 for the resilient support of a mattress 71 and when the intermediate berth is arranged in lowered position for daytime use the mattresses 71 for the lower and intermediate berths provide a seat cushion and cushioned backrest respectively for the accommodation of the three passengers occupying the tier of berths. The backrest is secured in its daytime inclined position by means of releasable connections 77 between the frame 63 and posts 64 and 65.

The various sleeping alcoves 45 are adapted to be enclosed at night by removable curtains (not shown) which are suspended from curtain rod 78 extending continuously across all of the accommodations at the aisle and secured to the posts 65 by suitable clamping devices 79. The alcoves are all provided with individual lighting fixtures 80 disposed upon the side wall 15 above windows 17 and inclined downwardly toward the interior of the alcoves. The upper berth area of the passenger compartment is provided at intervals with transoms 81 which may be opened for light and ventilation and which will be more fully described hereinafter. Supporting hooks 82, disposed in batteries of three, are provided upon each upper berth frame 61 at the aisle position where the occupants may hang clothing or the like behind the curtains enclosing the alcoves. In addition to the hooks 82, clothes hangers 83 as shown in Fig. 4 may be provided for the occupant of each berth and suspended respectively from the ceiling 16 for the upper berth occupant, from the upper berth frame 61 for the intermediate berth occupant and from the intermediate berth frame 62 for the occupant of the lower berth.

It will be noted from an examination of Figs. 45 1 and 2 that it might be said that the porter's berth enclosure 100 is located between the passenger compartment and the end zone of the car where it is convenient to either. The porter's berth is located at upper berth level adjacent 50 to the end zone of the car and is entered through the end bulkhead 20 as will hereinafter appear. The arrangement and construction details of the porter's berth are best shown in Figs. 5, 6 and 7 and the disposition of the berth in relation to the bulkhead 20 is best shown in Figs. 3 and 4. By providing the entrance to the berth through the end bulkhead the porter's accommodation is completely dissociated from the passenger compartment since it is necessary for the porter to enter the berth space from the juncture of transverse aisle 41 and end passageway 42 by means of steps 101 on the bulkhead.

The bulkhead 20 comprises a flat panel 102 extending from side wall 15, where it is secured 65 to angle 164, to the side aisle 18 where it is secured to post 165. Hollow framing members secured thereto rigidify the panel and include a horizontal member 103 extending continuously across the width of the bulkhead between posts 164 and 165 at the level of the porter's berth. A vertical framing member 104 located adjacent to a point approximately midway between the posts 164 and 165 extends from the member 103 to the floor 12 and serves to stiffen 70 the central area of the panel. This area of the

panel is further rigidified by horizontal members 105 extending upon opposite sides of the vertical member 104 to the respective posts 164 and 165 and disposed substantially midway between the reinforcing member 103 and floor 12. The panel 102 is cut away in the area of the porter's berth at that end adjacent the side aisle 18 to provide an opening 106 affording access to the berth. The opening 106 is defined at the lower side by reinforcing member 103 which serves the additional function of protecting the edge of the panel 102 and provides a smooth extended surface at the opening instead of the bare edge of the panel, as best illustrated in Fig. 7. The bulkhead panel extends to the ceiling of the car for a portion of its width approximating half the length of the porter's berth and is provided with hollow reinforcing frame members 107 and 108 adjacent the top edge at the ceiling and at the side edge bordering the opening 106 respectively. The panel 102 at the ceiling of the car is secured to a member 109 attached to the ceiling and at the opening 106 is bent around a flange of the reinforcing member 108 to provide a smoothly rounded surface 110 presented toward the opening. At the opposite side of the opening 106 the inwardly directed flange of post 165 is covered by a U-shaped protecting shield 111 presenting a smoothly rounded surface to the opening. A bar 112 extends across the entrance opening 106 from the edge 110 of the bulkhead panel to the covered flange 111 of the post 165 to both of which it is secured and affording a convenient grab for entering the berth and a support for clothes hangers 113 and safety straps 114.

The porter's berth enclosure 110 comprises a panel 120 spaced from the bulkhead panel 102 by the width of the berth and extending from the side wall 15 the full length of the berth and providing an end wall portion 122 extending across the end of the berth at the side aisle to the post 165 as best shown in Fig. 2. The enclosing panel is secured to post 165 and at the side wall is attached to an angle member 121 and throughout its length extends from the ceiling of the car to the lowermost portion of the berth so as completely to conceal the accommodation from the passenger compartment and is secured at the ceiling along the end wall portion 122 bordering the aisle 18, through the medium of angle member 67 which extends continuously from the post 165 and traverses all of the posts 65 to provide an attachment therefor as hereinbefore described. That portion of the enclosing panel extending along the length of the berth is secured to the car ceiling through the medium of a member 123 which together with the angle shaped longitudinal 67 provides a means of suspending the panel from the ceiling throughout its entire extent. Ventilating openings 124 are provided in the end wall 122 for the admission of air to the berth space and a safety bar 125 is disposed across the width of the openings to break up their size. Curtain rod 78 is anchored to the end wall 122 by means of clamping devices 79.

The berth per se comprises a rectangular frame 161 which serves to strengthen and rigidify the lowermost portion of the enclosing panel 120 while being supported in part thereby. The berth frame along one side and across one end is secured to panel 120 and end wall 122 respectively of the berth enclosure whereby to receive its support for those portions therefrom while at the same time

serving to stiffen the enclosure. At the end bulkhead side of the berth the frame 161 is secured to the bulkhead panel 102 through an intervening closure member 126 while at the end of the berth adjoining side wall 15 the frame is secured to and supported from the longitudinal frame member 68 by means of angle bracket 127 (see Fig. 6). Thus it will be seen that the porter's berth enclosure is rigidly constructed in a manner to form an integrated part of the car structure. The frame 161 as best shown in Figs. 6 and 7 carries a spring structure 170 for the resilient support of a mattress and bedding 171. Guard rods 128 are secured to the frame 161, one at each side and which at the entrance to the berth affords a convenient point of attachment for the safety straps 114. At the opposite side of the porter's berth the rod 128 is utilized as a support for safety straps 59 for the intermediate berth disposed immediately therebeneath and which are provided for all of the berths throughout the passenger compartment. Curtains (not illustrated) may be provided for the porter's berth to cover the entrance opening 106.

The porter's berth enclosure like the upper berth area throughout the passenger compartment is provided with a transom 81 but disposed individual to this accommodation and which may be utilized for additional light and ventilation. The transom is arranged in the side wall 15 and all of the transoms throughout the length of the car are disposed on the same level in the upper berth area. The transom comprises a solid sash 84 pivotally mounted intermediate its top and bottom in a frame 85 mounted in the side wall. The pivot for the sash is located more closely adjacent the bottom thereof to permit swinging the sash inwardly to provide a large ventilating opening and without interfering with a screen 86 secured over the sash opening in the outer side wall. The sash is adjustable to a plurality of positions by means of the pivotal mountings which comprise a bracket 87 on the sash at each side and hingedly engaged in brackets 88 on the sides of frame 85. Each bracket 88 includes a spring actuated mechanism engageable with means on the associated bracket 87 whereby the opening of the sash 84 may be stopped in any one of a plurality of positions to control the amount of air and light admitted. A sash pull 89 is provided for operation of the sash.

From the foregoing it will be seen that a sleeping accommodation has been provided for what might be termed an alcove sleeping car, wherein a plurality of accommodations disposed transversely of the car are arranged in tiers accessible from individual alcoves, which is individual to the car porter and which is independent of all other accommodations in the car. The porter's accommodation is disposed on the same horizontal plane with certain of the remaining accommodations in the car and arranged in vertically spaced relation over others and separated entirely from all of the other accommodations by means of the enclosure extending thereabout.

What is claimed is:

1. In a railway sleeping car having a passenger compartment containing a plurality of sleeping accommodations disposed transversely of the car and having a longitudinal side aisle, an end zone in the car, a bulkhead separating the end zone from said passenger compartment, an auxiliary sleeping berth between the passenger compartment and said end zone disposed in an upper portion of the passenger compartment, and an

entrance opening to the berth in said bulkhead, said berth being accessible only from the end zone of the car.

2. In a railway sleeping car having a passenger-compartment containing a plurality of sleeping accommodations disposed transversely of the car and having a longitudinal side aisle, a transverse bulkhead defining one end of the passenger compartment, an auxiliary sleeping berth adjacent to said bulkhead disposed in an upper portion of the passenger compartment, and an entrance opening to said berth in the bulkhead providing the only means of access to the berth, said berth being disposed transversely of the car.

3. In a railway sleeping car having a passenger compartment containing a plurality of sleeping accommodations disposed transversely of the car arranged in vertical tiers of berths placed one above the other and convertible to provide seating accommodations for daytime use and accessible from a longitudinal side aisle, an end bulkhead disposed transversely of the car defining one end of said passenger compartment, an auxiliary sleeping berth within the passenger compartment adjacent to said bulkhead disposed on a level substantially coincident with all of the sleeping accommodations at one level of said tiers and of a height at least substantially equal to that of such accommodations but less than the height of said compartment, and an opening through said bulkhead comprising the only means of access to said auxiliary berth.

4. In a railway sleeping car having a passenger compartment containing a plurality of sleeping accommodations disposed in vertical tiers of berths arranged in parallel overlying relationship and accessible from a longitudinal side aisle, all of said berths being disposed transversely of the car and certain of the berths being convertible to provide seats for daytime use of the occupants of the respective accommodations, a bulkhead disposed transversely of the car defining one end of said passenger compartment, an auxiliary sleeping berth adjacent to said bulkhead disposed on a level substantially coincident with all of the sleeping accommodations at one level of said tiers and of a height at least substantially equal to that of such accommodations but less than the height of said compartment, an opening through the bulkhead affording access to the auxiliary berth, and an enclosure disposed about the auxiliary berth adapted with the bulkhead to separate said berth from the remaining accommodations of the car whereby the berth is accessible only through said bulkhead.

5. In a railway sleeping car having a passenger compartment containing a plurality of sleeping accommodations disposed in vertical tiers of berths arranged in parallel overlying relationship and accessible from a longitudinal side aisle, all of said berths being disposed transversely of the car and certain of the berths being convertible to provide seats for daytime use of the occupants of the respective accommodations, a bulkhead disposed transversely of the car adjacent to one of said tiers of berths and defining one end of said passenger compartment, said last-named tier of berths including an auxiliary sleeping berth disposed in parallel relationship to another berth in the tier and at a level substantially coincident with all of the sleeping accommodations at a corresponding level of the respective tiers in the passenger compartment and occupying space of a height at least substantially equal to one of said berths but less than

the height of said compartment, an opening through the bulkhead affording the only means of access to the auxiliary berth, and means on the bulkhead affording access to said opening comprising steps.

6. In a railway car having spaced side walls connected by an end wall, a doorway in the end wall, a central longitudinal passageway leading from the doorway, a passenger compartment, a longitudinal side aisle extending the length of said compartment adjacent one of said side walls, passenger accommodations in said compartment including berths extending transversely of the car from the opposite side wall to said aisle and disposed in tiers each having three berths arranged in parallel overlying relationship, alcoves opening off of the side aisle affording access to the individual berths, a transverse bulkhead defining one end of said passenger compartment and substantially coextensive with said berths, an aisle extending transversely of the car adjacent to the bulkhead connecting said central passageway with the side aisle, an auxiliary sleeping berth parallel to the bulkhead and disposed at a level substantially coincident with all of the berths at a corresponding level of said respective tiers and occupying space of a height at least substantially equal to one of said berths but less than the height of said compartment, an opening in the bulkhead affording access to the auxiliary berth from said transverse aisle, and an enclosure disposed about the auxiliary berth associated with the bulkhead completely to separate said berth from the remaining accommodations of the car.

7. In a railway car having spaced side walls connected by an end wall, a doorway in the end wall, a central longitudinal passageway leading from the doorway, a passenger compartment, a longitudinal side aisle extending the length of said compartment adjacent one of said side walls, sleeping accommodations in the passenger compartment comprising berths extending transversely of the car from the opposite side wall to said aisle and disposed in tiers each having berths arranged in parallel overlying relationship at lower, intermediate and upper levels, alcoves opening off of the side aisle affording access to the individual berths, a transverse bulkhead defining one end of said passenger compartment and substantially coextensive with said berths, an aisle transversely of the car adjacent to the bulkhead connecting said central pasageway with the side aisle, an auxiliary sleeping berth parallel to the bulkhead and disposed at a level substantially coincident with all of the berths at said upper level, an opening in the bulkhead affording access to the auxiliary berth from said transverse aisle, an enclosure disposed about the auxiliary berth associated with the bulkhead completely to separate said berth from the remaining accommodations of the car, and means comprising steps on said bulkhead affording access to said opening.

8. In a railway car having spaced side walls defining a passenger compartment, a longitudinal side aisle extending the length of said compartment adjacent one of said side walls, sleeping accommodations in the passenger compartment comprising berths extending transversely of the car from the opposite side wall to said aisle and disposed in tiers each having berths arranged in parallel overlying relationship at lower, intermediate and upper levels, alcoves opening off of the side aisle affording access to the individual berths, an end zone in the car, a transverse bulk-

head separating the passenger compartment from said end zone, a longitudinal passageway in said end zone, an aisle extending transversely of the car adjacent to the bulkhead connecting said longitudinal passageway with the side aisle, one of said tiers of berths being disposed immediately adjacent to said bulkhead, an enclosure disposed about the berth of said last-named tier at the upper level and associated with the bulkhead completely to separate said berth from the other berths of the tier and from the remaining accommodations of the car, said other berths being accessible from an alcove in the passenger compartment and said enclosed berth being entered from said transverse aisle in the end zone, and means comprising an opening in said bulkhead affording access to the enclosed berth, said bulkhead having steps leading to said opening.

9. In a railway car having spaced side walls defining a passenger compartment, a longitudinal side aisle extending the length of said compartment adjacent one of said side walls, sleeping accommodations in the passenger compartment comprising berths extending transversely of the car from the opposite side wall to said aisle and disposed in tiers each having berths arranged in parallel overlying relationship at lower, intermediate and upper levels, alcoves opening off of the side aisle affording access to the individual berths, an end zone in the car, a transverse bulkhead separating the passenger compartment from said end zone, one of said tiers of berths being disposed immediately adjacent to said bulkhead, an enclosure disposed about the berth of said last-named tier at the upper level and associated with the bulkhead completely to separate said berth from the other berths of the tier and from the remaining accommodations of the car, said other berths being accessible from an alcove in the passenger compartment and said enclosed berth being entered from said end zone, and means comprising an opening in said bulkhead affording access to the enclosed berth.

10. In a railway car having spaced side walls defining a passenger compartment, a longitudinal side aisle extending the length of said compartment adjacent one of said side walls, sleeping accommodations in the passenger compartment, an end zone in the car, a transverse bulkhead separating the passenger compartment from said end zone and extending from said aisle to the opposite side wall, berths in the passenger compartment including a lower and an upper berth arranged in parallel overlying relationship immediately adjacent to said bulkhead, said lower berth being accessible from the passenger compartment, an enclosure disposed about said upper berth associated with the bulkhead completely to separate said berth from the lower berth and from the remaining accommodations of the car, and an entrance in said bulkhead to the upper berth whereby said upper berth is accessible only from the end zone of the car.

11. In a railway car having an end zone and a passenger compartment, a bulkhead separating the passenger compartment from the end zone, an aisle affording communication between said compartment and the end zone, and sleeping accommodations in the passenger compartment including berths arranged in parallel overlying relationship adjacent said bulkhead, one of said

berths being accessible only from the end zone of the car and the other only from the passenger compartment.

12. In a railway car having an end zone and a passenger compartment, a bulkhead separating the passenger compartment from the end zone, an aisle affording communication between said compartment and the end zone, sleeping accommodations in the passenger compartment including berths arranged in parallel overlying relationship adjacent said bulkhead, one of said berths being entered from the end zone of the car and the other from the passenger compartment, and an enclosure about the berth entered from the end zone separating said berth from the passenger compartment whereby said berth is accessible only from the end zone.

13. In a vehicle having spaced side walls, a passenger compartment, a longitudinal side aisle extending the length of said compartment adjacent one of said side walls, passenger accommodations in said compartment between said aisle and the opposite side wall, an end zone in the vehicle, a transverse wall separating the passenger compartment from said end zone and extending from said aisle to said opposite side wall, berths in the passenger compartment including a lower and an upper berth arranged in parallel overlying relationship immediately adjacent to said transverse wall, one of said berths being accessible only from the passenger compartment, an enclosure disposed about the other berth associated with the transverse wall completely to separate said berth from the remaining berth, and an entrance through said wall to said other berth whereby said berth is accessible only from said end zone.

14. In a vehicle having a passenger compartment including a plurality of passenger accommodations having a longitudinal aisle along one side thereof, a transverse wall defining one end of the passenger compartment, an auxiliary sleeping berth in the passenger compartment adjacent to said wall, and an entrance opening in the transverse wall providing the only means of access to said berth, said berth having a vertical height occupying not more than half the height of said passenger compartment.

15. In a vehicle having spaced side walls and an end wall, a doorway in the end wall, a central longitudinal passageway leading from the doorway, a passenger compartment, a longitudinal side aisle extending along one side of said compartment adjacent to one of said side walls, a transverse aisle connecting said central passageway with the side aisle at one end of the passenger compartment, passenger accommodations in said compartment accessible from said side aisle, at least certain of the accommodations having a seat for daytime use of the occupants convertible to provide a sleeping berth, a berth in said accommodations adapted to be arranged in parallel overlying relationship to said seat-berth, and an auxiliary sleeping berth accessible from said transverse aisle disposed substantially on a level with one of the berths in said accommodations and occupying space of a height substantially less than the height of said compartment.
